AUTOMATIC SPARK ADJUSTER

Henry J. De N. McCollum, Evanston, Ill.

Application February 24, 1933, Serial No. 658,381
Renewed October 31, 1935

8 Claims. (Cl. 180—77)

This invention relates to the automatic retardation of the ignition spark for internal combustion engines installed on road vehicles or motor cars of any description, and has for its object the temporary production of such retardation whenever the vehicle is started into motion from a condition of rest, or has its existing rate of motion substantially accelerated, or is being driven up a grade, under all of which conditions a substantial retardation of the moment of ignition of each cylinder charge of fuel beyond that at which the best results are obtained when running at uniform speed or under lighter loads, is desirable for smooth and efficient operation of the engine, and for the avoidance of internal strains and overheating. The spark is also retarded when the engine is idling.

The best form of apparatus embodying my invention, at present known to me, and sundry modifications thereof, are illustrated in the accompanying sheet of drawings, in which,

Fig. 1 is a plan view of a portion of an internal combustion engine and the circuit breaker for the ignition system thereof, with my invention applied thereto, certain parts being broken away and others shown in section.

Fig. 2 is a similar side elevation, on a smaller scale.

Fig. 3 is a view of a modification, Fig. 4, is a detail of another modification, and, Fig. 5 shows the invention applied to another form of ignition device.

Throughout the drawing like reference characters indicate like parts.

In all the figures of the drawing, the numeral 1 indicates the cylinder block of a standard form of motor for automobile construction, the numeral 2 is the intake manifold, and the numeral 3 is the carburetor therefor. The carburetor 3 has the usual throttle valve shaft 4, carrying stop arm 5, yielding forced toward stop 5a, so placed as to hold throttle valve in idling position, by tension spring 6, anchored at 7, and manually controlled by a lost-motion linkage 48 extending to accelerator pedal 9, normally retracted by expansion spring 10 confined between it and the footboard 11.

A standard form of rotary circuit breaker or spark timer for the ignition system having the cylindrical casing 29 is shown in Figs. 1 to 3 of the drawing. In the interior of said casing are pivoted at 23, 23, two circuit breaker arms 24, 24, carrying bearing lugs 28, 28, cooperating with multiple cam 21 secured to a shaft 22 geared to rotate with the engine crank-shaft. These breaker

arms 24, 24, are electrically connected to the binding post 26, while the fixed contacts 27, 27, with which they cooperate, are grounded. The springs 25, 25, normally hold the arms 24 against contacts 27 until the cam 21 momentarily separates the points one after the other and breaks the circuit, thereby producing the spark for ignition of each cylinder charge. The casing 29 is loosely journaled on cam-shaft 22, which rotates in a clockwise direction as indicated by the arrow in Fig. 1. The casing and circuit breaker arms 24 carried therein are prevented from rotating by rod 19 pivoted at one end to the external casing lug, or lever arm 20, and at the other end anchored in any desired way in a position which will properly time the moment of each breaking of the circuit and consequent spark production. If the lug 20 is moved slightly in a clockwise direction, looking at Figs. 1 and 2, so that the diametrical line $x-x$ is moved to position x^1-x^1 , the spark will be retarded to that angular extent.

In practically all modern motor cars the spark timing is automatically controlled by a centrifugal or other governing mechanism geared to the engine, so that the spark is automatically advanced by rotating cam 21 in a clockwise direction with respect to its axis more or less as the speed of revolution of the engine crank-shaft increases. Under usual conditions of operation the standard 4-cycle gas engine performs most efficiently with an advance of the ignition spark a number of degrees beyond the crank dead center. When starting, sharply accelerating or lugging, (i. e. laboring at very low speed on high gear) with a heavy load on the engine, however, the spark must be somewhat less advanced. These conflicting requirements, which sometimes arise at the same engine speed, have made it impracticable to set the centrifugal governing mechanisms so as to produce at their minimum operating speed the amount of spark advance best suited for the first class of conditions, such as the moderate running at a moderate speed along a level road with a lightly loaded car, because when the car is heavily loaded, or is going upgrade, or both, and is running at the same speed, the spark should be much less advanced. Consequently, the standard apparatus governed by engine speed and now used to automatically adjust, or time, the ignition spark are all set to produce a predetermined minimum spark advance which is too slight to produce highest efficiency under ordinary conditions of running on a smooth, level road, and this has to be done to

avoid an excess spark advance when starting, accelerating, or lugging.

My invention, hereinafter to be described more in detail, can be used with, and as supplementary to, the said standard automatic speed actuated spark control, in that it automatically retards the spark when the car is started, accelerated, or driven uphill, and that this is done independently of any contemporaneous speed responsive 10 adjusted governor control.

With approximately uniform load conditions, the spark should (generally speaking) be advanced proportionately to the engine speed, as every motorist knows, and the centrifugal governor fulfills this requirement, but has to be set 15 for level road conditions and does not compensate for any considerable increase in load at a given speed, such as occurs when a car is being driven up a steep grade. When climbing a hill 20 the throttle is opened wider, more combustible mixture is drawn into the cylinders for each cycle of operation, such larger charge is more quickly and sharply compressed, and the spark should be correspondingly retarded to prevent knocking, over-heating and straining of the motor, but 25 the centrifugal, engine-driven spark controller always maintains the same spark advance for the same speed no matter what the load and throttle conditions. Also, when the load on the 30 engine is suddenly increased by throwing in the clutch on starting or shifting to a higher gear, the spark should be retarded sharply, but if the centrifugal apparatus alone is in use, this retardation will not occur because it has been set to produce the greater angle of advance suitable for 35 other conditions.

I have discovered that both of these difficulties can be overcome if the extreme retardation of the 40 spark so desirable under the above recited special conditions is automatically effected by a device actuated by the combined influences of gravity and inertia, the simplest form of which is a small pendulum connected to the adjusting lug, or lever arm 20, of the circuit breaker, or ignition 45 timer.

Referring to Figs. 1 and 2, a pendulum weight 13 is there shown as suspended by rod 14 from shaft 12 journaled in the ears 16, 16, of the bracket 15, fastened to the top of the cylinder 50 block 1 by screws 45, 45. Cross pins 17, 17, prevent shaft 12 from sliding endwise. The numeral 18 designates a crank arm projecting upward from shaft 12, and to which one end of rod 19 is pivoted. The numerals 30 and 60 designate 55 pins limiting the oscillations of pendulum rod 14.

This embodiment of my invention, shown in Figs. 1 and 2, operates as follows: Assuming that the car moves from right to left (as indicated by the arrow between Figs. 1 and 2) when running forward, the inertia of the pendulum weight 13 will cause it to lag behind when the car is started, or has its motion sharply accelerated; thus swinging the parts 13, 14, 18, 19, 20 into the broken line positions shown, and retarding the spark to the desired extent, until gravity has had time to pull the pendulum back to its normal position shown in full lines. Similarly, when the car is going upgrade, the pendulum swings toward the broken line position and stays there, thus retarding the spark more or less so long as the car is on an upgrade. As the spark must not be retarded beyond the point corresponding to crank dead center, a stop, such as pin 60, must be provided to engage the train 70 of mechanism at some point, either at the pendu-

lum or at the timer, or at some intermediate point, to prevent any such excess retardation. Also, as it might not be advisable to have the spark abnormally advanced while going down hill, and certainly not when starting backwards 5 with the car, a second stop means, such as the pin 30, should be installed to prevent the pendulum swinging too far to the left of its normal vertical position, shown in full lines. It is assumed, of course, that the usual centrifugally 10 actuated timing device (not shown) operates on the cam 21, or cam shaft 22, and that no manually operated control device for timing the spark is provided, the latter usually being omitted from modern pleasure car equipment. 15

In the arrangement shown in Fig. 3, the car is supposed to travel from left to right (as indicated by the arrow) when running forward, and an inertia device of the electro-magnetic type, (the details of which were not invented by me) is 20 shown as another specific embodiment of the underlying principle of my generic invention. The body of mercury 33 in the horizontally extending glass tube 32, supported on bracket 35, there serves as the inertia controlled element, taking 25 the place of the pendulum bob 13 shown in Figs. 1 and 2. When the power clutch of the car engages and starts the car moving to the right, the mercury surges back to the left, and bridges contacts 34, 36, thus completing circuit 31 30 through battery 38 and solenoid 37. The magnetic attraction then pulls core 39 into solenoid 37, expanding spring 41, to which the core is connected by link 40. The lug, or lever arm 20, of the timer 29 is connected to this linkage at 35 any convenient point, and the spark is retarded accordingly. When the car is running at a uniform speed on a level road the mercury 33 does not touch the contact, or short electrode 34, solenoid 37 is de-energized and spring 41 pulls 40 the timer into its normally advanced position. When the car runs up a steep hill, short electrode 34 is again immersed in the mercury and the spark is retarded as is desired.

Obviously, a sliding weight, such as 53 (shown 45 in Fig. 4), having an anti-friction mounting 54 on a horizontal track 52, supported by a bracket 55 on any portion of the motor car, is the mechanical equivalent of the pendulum apparatus 13, 14, 12, shown in Figs. 1 and 2, for all purposes 50 of this invention. Compression spring 56 would perform the function of keeping the weight in one position so long as the car is running at a uniform speed along a level road, just the same as gravity holds the pendulum 13, 14, in one position 55 under similar conditions. Also, when the car starts, or accelerates, the inertia of weight 53 would cause it to lag momentarily, thus compressing spring 56 and moving to the right along track 52. Thereupon, link 119, which should be 60 connected to weight 53 at 57 and to lug 120 on timer 29 (if this sliding weight were substituted for a swinging pendulum), would rotate the timer casing in the desired clockwise direction and automatically retard the spark momentarily as before. 65 When the lag caused by the weight inertia has been overcome by spring 56 and the weight moved back to normal position (further acceleration of the car motion having ceased), the spark timing will return to normal. Also, whenever the car 70 is driven uphill weight 53 will tend to slide backward, compressing spring 56 more or less and correspondingly retarding the spark.

My invention has been hereinabove described as applied to the older form of timer and dis- 75

tributor in which the entire casing 29 is rotated in one direction or the other to vary the degree of spark advance, but in such construction the numerous wires (not shown) leading to the spark plugs and to the coil must be flexed with every adjusting movement, thus requiring the pendulum to do a considerable amount of work. In Fig. 5, however, I have shown it as applied to a more modern form of spark adjusting and distributing apparatus in which the casing 129 is stationary, and only an internal plate (not shown) which carries the circuit breaker arms 24, 24, and cooperating contacts 27, 27, rotates back and forth about shaft 22, being controlled for this purpose by lever arm 220 which projects radially from it through a slot 221 in the casing. The spark plug wires 61, 61, and the wire 62 to the coil then pass through the stationary cap 63 of casing 129 to the stationary contacts (not shown) of the stationary distributor head. The pendulum 113 of my invention can then be suspended from a pivot 112 on the exterior of casing 129, and the pendulum rod 114 is provided with a slot 118 through which the lever arm 220 projects. The pendulum then has to do only the work of rotating back and forth the said light plate, which carries the circuit breaker arms and the cooperating contacts, and the apparatus is much more sensitive, thus permitting the use of a much lighter pendulum weight. Also, its operation is maintained uniform at all times, being unaffected by variations in stiffness of the lead wires, such as might develop with age, or from readjustment of the wires such as might result from rewiring of the ignition system, etc.

It will thus be seen that when my invention, in whatever form it is embodied, is combined with the centrifugal, or other speed actuated, form of automatic spark adjuster, the resultant timing of the spark is a joint function of the two devices. If the engine is unloaded and running slowly enough to cause the centrifugal apparatus to retard the spark to the minimum of which it is capable, and the clutch is thrown in, the pendulum will temporarily further retard the spark. If the car is running at a speed such that the spark has been advanced a given number of degrees, and is suddenly accelerated, the pendulum will also momentarily further retard it to a greater or less extent according to the sharpness of the acceleration, and will thereafter gradually surrender all control of the timing to the centrifugal apparatus. If no centrifugal apparatus were employed, but the spark timing were manually effected, my invention would still automatically retard the spark during the desired periods above defined.

Various other changes could be made in the details of construction here illustrated and described, and equally without departing from the underlying novel principle of my invention; which involves the use in some way of the inertia or weight of an element loosely mounted with reference to the running gear of a motor car, to automatically retard the time of the ignition of the charge whenever the said element is suddenly put into motion, or accelerated in motion, or the car is driven onto an upgrade.

An additional automatic spark control which may be used in combination with my above described invention, or independently thereof, is also illustrated in Figs. 2 and 1. Referring to Fig. 1 another lug 120 is shown projecting from the other side of casing 29 and carrying a pin 149 projecting up through a slot 44 in a link 42,

which is pivoted at 43 to the accelerator linkage 8. The parts are so proportioned that after the retraction of the accelerator pedal 9 has allowed the throttle valve to assume idling position and the lost motion connection 48 in linkage 8 begins 5 to open, the left-hand end of the slot 44 in link 42 will engage the pin 149, and the final movement of the accelerator pedal to its position of rest will retard the spark to zero position. This permits slow and smooth idling and consequent economy 10 of fuel. The above described series of operations would also occur whenever the modified inertia element of Fig. 4 should be employed, with its rod 119 connected to lug 120, as previously described. When the accelerator pedal is pressed 15 down to open the throttle valve and the clutch has become sufficiently engaged to accelerate the motion of the car, the spring 56, or pendulum weight 13, first advances the spark to the normal position for which the centrifugal governing device is set, and thereafter the manipulation of the accelerator has no effect on the timing (because of the length of slot 44) until the parts again return to idling position. While the accelerator pedal is pressed down to any extent sufficient to 20 open the throttle valve beyond its idling position, pin 149 may then move freely in slot 44 without coming in contact with either end thereof, so that the spark timing is then solely under control of pendulum 13 or sliding weight 53, which ever has 25 been installed, together with the usual centrifugal governor.

Of course, in the modification shown in Fig. 4 the effective pull of spring 10 on lug 120 must slightly exceed the pull of the spring 56 in the 30 opposite direction in order to have the spark retardation thus produced by the pedal. When the car is started, or accelerated, or running uphill, however, the accelerator pedal 9 will always be depressed, so that the lost motion connection 40 44-149 will release lug 120, and spring 56 and weight 53 will then have sole control of the timer member 29, allowing the inertia or the gravitation of the weight 53 to properly retard the spark during the starting and accelerating periods, or 45 when hill climbing, in the desired manner before described.

Other means actuated by the pendulum, or equivalent inertia-controlled element, and operative to retard the spark, might be substituted for 50 the purely mechanical devices herein shown which mechanically shift the point in each cycle of engine operation at which the circuit producing the spark is closed or opened, as the case may be.

Having described my invention, I claim:

1. In a spark timing apparatus for a gas propelled motor car having adjustable rotary circuit breakers normally set to produce the spark igniting the cylinder-charge somewhat in advance of the dead center position of the crank of the engine propelling said car, the combination of mechanism comprising an element of substantial weight so mounted on said car as to be movable longitudinally thereof, with means actuated by said weight element operative to retard the spark 60 whenever said weight element moves toward the rear of the said car; whereby, whenever the said car is started forward or has its motion in that direction substantially accelerated, the temporary lag in motion of said weight element will contemporaneously retard the spark.

2. A combination such as defined in claim 1 in which said weight element is a pendulum.

3. An apparatus such as defined in claim 1 in which said weight element is slidingly mounted 75

on a horizontal track combined with a spring normally forcing said weight toward the front of the said car.

4. An apparatus such as defined in claim 1 combined with means for preventing said weight element from moving far enough toward the rear of said car to retard the spark beyond the dead center position of the said engine crank.

5. An apparatus such as defined in claim 1 combined with means for preventing said weight element from moving to any position that would advance the spark beyond the predetermined normal angle.

6. In a spark timing apparatus for use on a motor car having a throttle controlled carburetor delivering a combustible mixture to the intake manifold of the engine for propelling said car and an adjustable rotary circuit breaker normally set to produce the spark for igniting said mixture somewhat in advance of the arrival of the crank of said engine at dead center position, the combination, with said above described apparatus of mechanism comprising an element yieldingly mounted on such car and connected to a spark-timing member of such circuit breaker, yielding means normally tending to hold said element in a position which maintains such a normal spark timing, and means responsive only to sudden movements and acceleration of movements of the car for automatically moving said element in a direction which will retard said spark; whereby such spark retardation is ensured whenever said car is started or accelerated in forward motion, or such carburetor throttle is brought to idling position.

7. In a spark timing apparatus for use on a motor car having a throttle controlled carburetor delivering a combustible mixture to the intake manifold of the engine which propels said car,

with a spring-retracted pedal controlling said throttle and an adjustable rotary circuit breaker having a member controlling the timing of the spark for igniting said mixture normally set to produce such spark somewhat in advance of the arrival of the crank of said engine at dead center position, the combination, with said above described apparatus, of a lost-motion connection from such pedal to said spark-timing member and mechanism comprising an element yieldingly mounted on such car and connected to said spark-timing member of such circuit breaker, yielding means normally tending to hold said element in a position which maintains such a normal spark timing, and means responsive only to sudden movements and acceleration of movements of the car for automatically moving said element in a direction which will retard said spark; whereby such spark retardation is ensured whenever said car is started or accelerated in forward motion, or such carburetor throttle is brought to idling position.

8. In a spark timing apparatus for a motor car having an internal combustion engine for propelling it and an adjustable rotary circuit breaker normally set to produce the spark igniting the cylinder charge somewhat in advance of the dead-centre position of the crank of said engine, the combination of mechanism comprising an element so mounted on said car as to be movable longitudinally thereof, with means actuated by said element and operative to retard the spark whenever said element moves toward the rear of the said car; whereby, whenever said car is started forward, or has its motion in that direction substantially accelerated, the temporary lag in motion of said element will contemporaneously retard the spark.

HENRY J. DE N. McCOLLUM.
